UNITED STATES PATENT OFFICE.

ROLAND H. RITTER, OF PHILADELPHIA, PENNSYLVANIA, ASSIGNOR TO NATIONAL METAL EDGE BOX COMPANY, OF PHILADELPHIA, PENNSYLVANIA, A CORPORATION OF PENNSYLVANIA.

BOX-STAYING MACHINE.

1,243,877.

Specification of Letters Patent. Patented Oct. 23, 1917.

Application filed May 15, 1917. Serial No. 168,863.

To all whom it may concern:

Be it known that I, ROLAND H. RITTER, a citizen of the United States, residing at Philadelphia, county of Philadelphia, and 5 State of Pennsylvania, have invented a new and useful Improvement in Box-Staying Machines, of which the following is a full, clear, and exact description, reference being had to the accompanying drawings, which 10 form a part of this specification.

My invention relates to that class of machines in which a die is caused to descend upon a stationary anvil, between which is placed a box and stay or other articles to be 15 clamped together or compressed.

In box staying machines, such as described in connection with my invention, the anvil is usually of rectangular cross section and positioned diamond-wise, with its 20 horizontal active edge uppermost. Against this edge and contiguous surfaces the die descends and does its work.

My invention may, however, be applied with equal effectiveness to machines in 25 which anvil and die present round or flat horizontal surfaces between which the compression takes place.

In the operation, for example, of staying a box angle, the operator places the two 30 sides to form said angle upon the faces of the anvil contiguous to the active edge, and holds them close with his fingers during the action of the die in the application of the stay. This requires that the operator shall 35 keep his fingers close to the joint and yet not too close. To decrease danger of accident and protect the operator, it is desirable to provide some safety device therefor.

The object of this invention is to provide 40 such a safety device, wherein appropriate parts are supplied, carried by the die holder and projecting downwardly in advance of the die, and so positioned as to contact with the operator's fingers if he has inadvertently placed them within the danger zone, and thereby be made to immediately disconnect the die holder from its operating arm, and prevent its further descent toward the anvil.

50 I will now describe in detail a machine embodying my invention, in connection with the accompanying drawings, in which:

Figure 1 is a side elevation of a box stay-

ing machine with my invention applied thereto.

Fig. 2 is a sectional view of a portion of the machine.

Fig. 3 is an enlarged elevational view of the part of the machine carrying my invention.

Fig. 4 is an end view of parts shown in Fig. 3, partly in section, showing my tripping mechanism.

Fig. 5 is a similar view, to a larger scale, illustrating the tripping action.

Fig. 6 is an enlarged sectional plan view of parts shown in Fig. 4.

Fig. 7 is a perspective view of a part of the machine carrying part of my device.

Fig. 8 is a similar view showing another part of my device.

Fig. 9 is an end view of the parts shown in Fig. 8.

To understand the application of my invention to a box staying machine, it is advisable to first explain the general construction and mode of operation of such a machine.

The metal staying strip *a* is carried on a drum *b* at the rear of the machine, and led through a throat *c* to the under side of the die *d*. The strip is fed forward by a pawl *e* carried by a block, which slides along throat *c* and is actuated by a bell-crank *f*, which is given an oscillating movement by connection with the main crank pin *g*. The staying strip is held by a pawl *h* as it is fed forward.

Die *d* is actuated vertically by an elbow lever *j* and a link *k*, operated by a connecting rod *m* from main crank pin *g*. The main crank is on a shaft *n* which is connected by gearing *o* with a driving shaft *p* carrying a belt pulley *q*. A foot lever *r* operates a clutch at *r'* connecting shaft *n* with gearing *o*, such that by pressing down the foot lever the clutch is opened and driving connection with the die holder is broken. In order that stoppage of the machine may 100 be instantaneous when this takes place, shaft *n* is engaged by an adjustable friction clamp *s*. It is unnecessary to describe this mechanism in further detail, as it is old and well understood in the art.

Die *d* is carried by a die holder *t* slidable in ways *u* on the frame of the machine. The anvil *v* is rigidly mounted on the front of

said frame directly below the die. A finger guard, of light frame construction, comprising yoke-shaped end pieces 10, is carried by the die holder, straddling the same at both ends, and supports horizontal guarding rods 11 on both sides of the die and slightly in advance thereof. These rods are supported close to the working edge of the die, not close enough to interfere with the normal working of the machine, but sufficiently close to surely contact with the operator's fingers if they should be in dangerous position, as shown in Fig. 4. The guard frame 10 is slideable vertically and when raised, as by contact with the operator's finger as before stated, it springs a catch, which instantly disconnects die holder *t* from its driving link *k*, and arrests the downward movement of the die by means to be now described.

The end of link *k*, which embraces pin 12 on the die holder, is cut away as shown in Fig. 3, not so as to affect the normal raising and lowering of the die holder by the link, but so that the end of the link may be readily slipped off of pin 12, and thus instantaneously stop the action of the die holder without stopping the machine.

A bolt 13 is slidably mounted in the die holder, beneath and parallel to pin 12. Bolt 13 carries a cam face 14 which on occasion acts upon a pin 15 projecting from the end of link *k* to move said pin to one side, thus sliding the end of link *k* off of pin 12.

Bolt 13 is held out of action against a spring 16 by a latch arm 17 pivoted to the bolt at 170 in a cut-away portion thereof. When bolt 13 is pulled out, latch arm 17 is turned from the horizontal down to the vertical position shown in Fig. 4, thus holding the bolt out. The latch arm is held in this position by its lower end being caught by a projection 18, see Figs. 6, 8 and 9.

Projection 18 is carried by a sleeve 19, turnable on the shaft 23 hereinafter mentioned and carries an actuating arm 21.

A shaft 23 passes through sleeve 19 and carries at each end arms 24, which also overlay the die holder, and are provided with pins 25, which have loose hole connection with the end pieces 10 of the before mentioned guard frame. Spring 22 overlies arm 21 when the die holder is raised and serves to return this arm to normal position after the operation of the safety device, as herein-after described.

Arm 21, connected with sleeve 19, carries at its other end a pivoted dog, one end 26 of which overlies a lip 24' projecting from the contiguous arm 24, and the other end 24 of which extends beside a short lever 28, and is held in this position by a spring 29.

The mechanism so far described, except the spring 22, is carried by the die holder and moves with it. When the die, in de-

scending, brings frame rods 11 against any obstruction, such as the operator's fingers, the guard frame is raised in a perfectly parallel manner, as the end pieces 10 are hung on arms 24 which are rigidly connected together by the shaft 23. In moving upward the guard frame raises the ends of levers 24, and therewith, by reason of lip 24' and dog 26, the end of arm 21. This turns sleeve 19 sufficiently to force latch arm 17 from projection 18, when said arm flies up to the horizontal as indicated in Fig. 5, resulting in the shooting of bolt 13 by its spring 16.

This disconnects link *k* from the die holder, as before described. Simultaneously the serrated end 30 of bolt 13 strikes the stationary head and prevents the further descent of the latter to do harm to the operator's fingers or otherwise.

Bolt 13 carries a ratchet toothed piece 30 on its inner end, and when the bolt is shot as just described, this serrated surface brings up against a finger 31 pivoted in the frame of the machine. At the following upward movement of the die holder, the serrated piece 30 will turn finger 31 about its pivot, which in rising will thus force bolt 13 away from it, until it is pushed out to its normal set position. In this outward movement of the bolt, a pin 32 on the latch lever is confined beneath a guide piece 33 and draws said lever down into latching position again with projection 18, the latter, together with the sleeve 19 and levers 21, being merely spring-held and yielding to allow the lever 17 to latch. When the latch has been sprung and the bolt shot as above described to disconnect the die holder from the driving mechanism, the following means is provided for linking it up again.

An arm 34 is pivoted on the projecting end of pin 12 and extends upward having a slot which engages a pin 35 on link *k*. When the link is disconnected from the die holder, it continues its downward motion, and pin 35 slips downward in its slot. In the return motion, when lever *j* has pulled link *k* up to engaging position again with pin 12, pin 35 reaches the upper end of the slot in arm 34, and this light pin and link begin to raise the die holder. However, pin 12 is located, not in the center line of link *k*, but beyond said center line. Therefore, when the die holder commences to be lifted as described, pins 12 and 35 tend to straighten out into the center line of link *k* and draws the cut-away end of said link back again in position about pin 12.

In the downward movement of the die, doing its work, if the guard frame contacts with the work and is thereby raised, it is not desired to disconnect as above. To arrange for this, a stop 36 is attached to the ways *u* of the machine, in vertical alinement below the head of lever 28, and at the right level to act upon lever 28 when the die and guard

frame have descended below the danger line, say within a quarter inch of the anvil.

Thus the guard frame may contact with the work upon the anvil and be raised at every action of the machine, but just before that takes place, stop 36 will have turned lever 28, which in turn acts upon the end 27 of the dog pivoted to arm 21, to turn its other end 26 out of engagement with lip 24. The raising of the guard frame, therefore, merely raises the ends of arms 24 and turns shaft 23, connecting said arms. The dog being free from lip 24', arm 21 is not affected by this action and sleeve 19 is not turned to trip the latch lever.

Having now fully described my invention, what I desire to claim and protect by Letters Patent is:

1. In safety stops for machinery, the combination with a member the operation of which it is desired to automatically arrest, of driving mechanism, a releasable driving connection between the driving mechanism and said member, a tripping lever, means controlled by the tripping lever to release said driving connection, a guard carried by, and retractable relatively to, said member upon meeting an obstruction, connections between the guard and the tripping lever adapted, upon such retraction of the guard in the forward movement, to allow the operation of the tripping lever and the driving connection releasing means, and means, operable when the guard in its normal operation has passed in its forward movement beyond a predetermined point, to sever the connections between the guard and the tripping lever, thereby preventing the release of the driving connection by the retraction of the guard.

2. In safety stops for machinery, the combination with a member the operation of which it is desired to automatically arrest, of driving mechanism, a releasable driving connection between the driving mechanism and said member, a tripping lever, means controlled by the tripping lever to release said driving connection, a guard carried by, and retractable relatively to, said member, connections between the guard and the tripping lever adapted, upon the retraction of said guard in the forward movement of said member, to allow the operation of the tripping lever and the driving connection releasing means, means operable in the rearward movement of said member to restore to normal position said tripping lever and the said means controlled thereby, and means, operable when the guard in its normal operation has passed in its forward movement beyond a predetermined point, to sever the connections between the guard and the tripping lever, thereby preventing the release of the driving connection by the retraction of the guard.

3. In safety stops for machinery, the combination with a member the operation of which it is desired to automatically arrest, of driving mechanism, a releasable driving connection between the driving mechanism and said member, a spring actuated bolt adapted to release said driving connection, a tripping lever pivotally attached to said bolt, a guard carried by, and retractable relatively to, said member, and connections between the guard and the tripping lever normally holding the latter in position to restrain the bolt from operation but adapted, upon the retraction of the guard, to be operated to release the tripping lever, thereby allowing the bolt to operate.

4. In safety stops for machinery, the combination with a member the operation of which it is desired to automatically arrest, of driving mechanism, a releasable driving connection between the driving mechanism and said member, a spring actuated bolt adapted to release said driving connection, a tripping lever pivotally attached to said bolt, a guard carried by, and retractable relatively to, said member, connections between the guard and the tripping lever normally holding the latter in position to restrain the bolt from operation but adapted, upon the retraction of the guard, to be operated to release the tripping lever, thereby allowing the bolt to operate and swing the tripping lever away from locking position, means operable in the rearward movement of said member to return the bolt, and a guide, coöperating with the tripping lever, in the return movement of the bolt, to return the tripping lever to position to latch with said connections.

5. In safety stops for machinery, the combination with a member the operation of which it is sought to automatically arrest, of driving mechanism, a releasable driving connection between the driving mechanism and said member, a guard carried by, and retractable relatively to, said member, a turnable device, a pair of arms thereon, connecting means between said guard and said arms effecting the operation of the latter when the guard is so retracted, a contrivance adapted when actuated to effect the release of said driving connection and a tripping lever normally held in position by said turnable device to restrain said contrivance from actuation but adapted, when said arms are moved and said device is turned by the retraction of the guard, to release said contrivance, thereby releasing the driving connection.

6. In safety stops for machinery, the combination with a member the operation of which it is sought to automatically arrest, of driving mechanism, a releasable driving connection between the driving mechanism and said member, a guard carried by, and

retractable relatively to, said member, a contrivance adapted when actuated to effect the release of the driving connection, a turnable shaft and sleeve carried by said member, an arm on the shaft connected with said guard, an arm on the sleeve, a connection between said arms, and a tripping lever normally held in position by said sleeve to restrain said contrivance from actuation but adapted, when said arms are moved and said sleeve is turned by the retraction of the guard, to release said contrivance, thereby releasing the driving connection.

7. In safety stops for machinery, the combination with a member the operation of which it is sought to automatically arrest, of driving mechanism, a releasable driving connection between the driving mechanism and said member, a guard carried by, and retractable relatively to, said member, a contrivance adapted when actuated to effect the release of the driving connection, a turnable shaft and sleeve carried by said member, a pair of arms on the shaft connected with opposite ends of the guard, two arms on the sleeve located in proximity to the other two arms respectively, a connection between each two approximating arms, and a tripping lever normally held in position by said sleeve to restrain said contrivance from actuation but adapted, when said arms are moved and said sleeve is turned by the retraction of the guard, to release said contrivance, thereby releasing the driving connection.

8. In safety stops for machinery, the combination with a member the operation of which it is sought to automatically arrest, of driving mechanism, a releasable driving connection between the driving mechanism and said member, a guard carried by, and retractable relatively to, said member, a contrivance adapted when actuated to effect the release of the driving connection, a tripping lever normally holding said contrivance

from operation, a turnable device normally holding said tripping lever in normal position but adapted to be turned to release the tripping lever and thus allow said contrivance to operate, an arm on said turnable device, another movable arm connected with said guard and movable thereby when the latter is retracted, a disruptable connection between said arms enabling the second arm to operate the first and thus turn said device and release the tripping lever, and means, operable when the guard in its normal operation has passed beyond a predetermined point, to disrupt the last named connection. 50 55 60

9. In safety stops for machinery, the combination with a member the operation of which it is sought to automatically arrest, of driving mechanism, a releasable driving mechanism between the driving mechanism and said member, a guard carried by, and retractable relatively to, said member, a contrivance adapted when actuated to effect the release of the driving connection, a tripping lever normally holding said contrivance from operation, a sleeve normally holding said tripping lever in normal position but adapted to be turned to release the tripping lever and thus allow said contrivance to operate, arms at opposite ends of the sleeve, a shaft on which said sleeve turns, arms on opposite ends of the shaft, dogs, one at each end connecting an arm on the sleeve with the adjacent arm on the shaft, means at opposite ends of the guard connecting the same with the arms on the shaft, and means, operable when the guard in its normal operation has passed beyond a pre-determined point, to move said dogs out of connecting position.

In testimony of which invention, I have hereunto set my hand, at Philadelphia, on this 10th day of May, 1917.

ROLAND H. BITTER
